NOLIE DIMICK, OF BLACK ROCK, OREGON.

SNAP-HOOK.

1,263,346.

Specification of Letters Patent. Patented Apr. 16, 1918.

Application filed June 27, 1917. Serial No. 177,334.

To all whom it may concern:

Be it known that I, NOLIE DIMICK, a citizen of the United States, residing at Black Rock, in the county of Polk and 5 State of Oregon, have invented new and useful Improvements in Snap-Hooks, of which the following is a specification.

This invention relates to snap hooks, and more especially to the locking devices for 10 closing the throat of the hook; and the object of the same is to improve the construction of such a locking device so as to leave nothing projecting beyond the exterior of the hook or the guard, and to 15 provide means for unlatching the catch and swinging the guard to open the throat of the hook without taking the tension off of the latter.

These and other objects are accomplished 20 by constructing the device in the manner hereinafter more fully described and claimed, and as shown in the drawings wherein:—

Figure 1 is a side elevation of what 25 might be called the front of this device with the parts closed.

Fig. 2 is a side elevation of the opposite or rear side of this device, with the parts open.

30 Fig. 3 is a front edge view of the hook detached from the guard, and Fig. 4 is a lower end view of the guard shown as disconnected and raised a little above the upper end of the shank of the hook illustrated 35 in Fig. 3 to illustrate their relative positions.

Fig. 5 is a section on the line 5—5 of Fig. 1.

The hook proper comprises a bill 1 whose 40 tip 2 is rabbeted at its outer side as at 3, the numeral 4 designates the bend of the hook, and 5 is its shank whose upper portion is reduced in thickness as at 6, and provided in one side face with a cavity 7 constituting a keeper as described below, 45 this face being beveled off as at 8 from the cavity to the inner edge of the shank. The guard 10 is substantially triangular in side elevation, is solid at what might be called 50 its outer side 11 and channeled as at 12 at its inner side to pass astride the reduced portion 6 of the hook-shank, and through the walls of said channel and the upper portion of said reduced shank is passed a 55 pivot 13. This may be a bolt, and by pref-

erence it passes also through eyes in the arms of a clevis 14 from which the snap hook is suspended as usual—however, I do not wish to be limited in this particular. The lower edges of said walls of the channel are beveled off as at 15 to complement shoulders 5' on the sides of the shank 5, and the lower end 16 of the solid portion 11 extends downwardly from the bevels 15 across the throat of the hook and across its bill, the lower face of this portion 16 being provided with a recess 17 to receive the tip 2 of the bill 1, and the outer wall 18 of said recess engaging the rabbet 3 when the parts stand closed as indicated in Fig. 1. 60 All parts thus far described may be made from castings or drop forgings, possibly bored to form the cavity 7 and the holes for the pivot 13, as well as the holes in the arms of the clevis if the latter be employed—therefore the structure is extremely simple and economical in manufacture. Without any means whatever for locking the guard when it stands across the throat of the hook, such throat is closed 65 thereby when the hook hangs as seen in Fig. 1, because the weight of the solid side 11 of the guard is sufficient to swing it into the position here shown and the tension of a load applied to the bend 4 of the hook 80 does not interrupt. However, I prefer to employ the locking devices next to be described.

A hole 20 is bored through the rear wall of the guard about where shown in Fig. 2, 90 and a hole 21 completely through both walls, and in said rear wall is cut a groove 22 connecting these holes. Mounted in the hole 20 is a catch 23 having a beveled tip 24, mounted in the hole 21 is a pin 25, and disposed in the groove 22 is a bar 26 connecting the rear ends of the catch and pin. These three elements may well be formed integrally, and when put in place the beveled tip of the catch stands within the channel 100 12 of the guard while the pin projects completely through to the other side as seen at 25 in Fig. 1. Through the pin is passed a stop in the form of another pin (perhaps a split pin) 27, and around the pin 25 is 105 coiled a spring 28 whereof one end rests on this stop and the other end rests against the inner face of the rear wall of the guard so that the normal tendency of the spring is to hold the bar 26 seated within the groove 22, 110

the tip of the catch projecting into the channel to engage the cavity 7 as best seen in Fig. 5.

With the parts constructed as described and properly assembled, the guard is unlocked by pressing on the front end of the pin 25. This moves the entire device against the tension of the spring 28, and disengages the tip 24 of the catch 23 from the keeper 10 or cavity 7 in the reduced portion 6 of the shank of the hook. Now the guard may be swung aside as seen in Fig. 2, and the ring or other element with which the hook is to be engaged can be passed over its tip 2 and dropped into its bend 4. Thereafter the guard is swung back to position, or perhaps allowed to fall back to position by its own weight, when the beveled tip 24 of the catch rises up the bevel 8 of the reduced portion 20 6, and the spring 28 causes the tip to slide into the cavity or keeper 7 in a manner which will be clear. As the guard reaches its closed position, its recess 17 passes over the tip 2 of the bill, and the wall 18 falls 25 into the rabbet 3 so that the extremity of the bill is now thoroughly inclosed and protected; and if the exterior configuration of the hook and the guard has received proper attention in the process of manufacture, 30 there are now no projecting parts thereon against which extraneous objects might catch. Moreover, all exposed parts of the locking mechanism stand normally substantially flush with the face of the guard, and 35 if said parts are accurately fitted to the holes and channel, little or no rain or snow can enter to interfere with the successful action of the device.

Copies of this patent may be obtained for five cents each, by addressing the "Commissioner of Patents, Washington, D. C."

What is claimed as new is:—

1. In a snap hook, the combination with 40 the hook having a cavity in one side face of its shank, and a pivot bolt through the upper end of the latter; of a guard channeled to embrace said shank and pivotally mounted on said bolt, a catch slidably mounted in 45 a hole in one wall of the channeled portion of the guard and adapted to move on a line parallel with said pivot bolt to engage said cavity when the guard is closed against the tip of the hook, the body of the guard having a hole through it near said first-mentioned hole and a channel connecting the two holes, a spring-actuated push-pin in the last-named hole, and a bar connecting said pin and said catch and lying normally in said 55 channel.

2. In a snap hook, the combination with 60 the hook comprising a shank, a bend, and a bill, one of said parts having a cavity in its side face; of a channeled guard embracing 65 the shank of said hook, a main pivot connecting the hook and guard, the latter having a recessed lower end adapted to engage the bill of the hook when the guard is closed, said guard having a hole opposite said cavity 65 and a groove leading radially from said hole, a catch in the hole and a bar in the groove, both movable parallel with the length of said main pivot, a spring connecting the remote end of said bar with the 70 guard and normally projecting the tip of the catch, and a push-pin for moving said bar against the tension of the spring, for the purpose set forth.

In testimony whereof I affix my signature. 75
NOLIE DIMICK.
